(57) **CLAIM**

I claim the ornamental design for the stile end cap, as shown and described.

DESCRIPTION

FIG. 1 is a perspective view of a stile end cap as assembled onto a stile which is drawn in dashed lines;

FIG. 2 is a perspective view of a pair of the stile end caps shown in exploded view from a stile drawn in dashed lines;

FIG. 3 is a top plan view of the stile end cap; and

FIG. 4 is a left side elevation view of the stile end cap;

FIG. 5 is a front elevation view of the stile end cap;

FIG. 6 is a right side elevation view of the stile end cap;

FIG. 7 is a rear elevation view of the stile end cap; and,

FIG. 8 is a bottom plan view of the stile end cap.
